UNITED STATES PATENT OFFICE.

ROBERT E. MURPHY, OF LOWELL, MASSACHUSETTS.

SKEIN-WASHING MACHINE.

SPECIFICATION forming part of Letters Patent No. 680,878, dated August 20, 1901.

Application filed July 6, 1900. Serial No. 22,737. (No model.)

To all whom it may concern:

Be it known that I, ROBERT E. MURPHY, a citizen of the United States, residing at Lowell, in the county of Middlesex and Commonwealth of Massachusetts, have invented a certain new and useful Improvement in Skein-Washing Machines, of which the following is a specification.

My invention relates to skein-washing machines; and it consists in the devices and combinations hereinafter described and claimed.

The objects of this invention are thoroughly to cleanse the skeins equally in all parts by repeatedly passing them through the washing liquid and by subjecting them to the action of squeeze-rolls after each immersion in said liquor; to prevent the "hairing out" of the yarn or the projection of the fibers from the yarns by always introducing the same end of the skein first into the washing liquid and keeping the same end of the skein always in advance in its passage through said liquid; to prevent the tangling of the yarns of the skein with each other, and to perform the operation in less time and with less help than is now commonly used.

Means are provided for changing the point of support of the skein on the "sticks" or poles upon which the skeins are suspended after each immersion of the skeins and for separating the squeeze-rolls to allow the passage of the sticks between said rolls, said squeeze-rolls immediately after the passage of the sticks between them closing upon the skins hung on said sticks.

In the accompanying drawings, on four sheets, Figure 1 is a right side elevation of a machine constructed in accordance with my invention; Fig. 2, a left side elevation of a portion of the same at the end which carries the squeeze-rolls; Fig. 3, a side elevation of the squeeze-rolls, the sprocket-wheel on the lower squeeze-roll, and the means of separating the squeeze-rolls; Fig. 4, a rear elevation of the machine or an elevation of the end which carries the squeeze-rolls; Fig. 5, a vertical transverse section on the line 5-5 in Fig. 1; Fig. 6, a front elevation of the cam which operates the skein-shifting device and the upper part of the lever immediately operated thereby.

The washing vat or tank A is of any usual

construction and is represented as supported by means of legs upon the floor or ground B. On suitable stands C C', rigidly secured, as 55 by bolts c c', to the sides of the tank A, near one end of the same, are journaled the main shaft D, the shaft E of the lower squeeze-roll e, and the intermediate shaft F. The main shaft D is provided with fast and loose pulleys d d' and is driven by a belt from any suitable motor in an obvious manner. The shaft F is driven by the pinion d' and intermediate gear f, fast on the shafts D and F, respectively, the gear f engaging another 60 gear e', fast on the shaft E. The shaft E has fast thereon at each end of the lower squeeze-roll e a sprocket-wheel e² e³ to carry an endless sprocket-chain G G', each chain running on grooved carrier-rolls g g' g², these 65 chains and rolls being duplicated at each side of the tank within the same, the chains running parallel with each other above the washing liquid toward the squeeze-rolls and below the surface of said liquid in the return direction. At suitable regular intervals, each interval being longer than a skein 70 S, clips H are attached to said chains, the clips on one chain being exactly opposite the clips on the other chain. The sticks or poles 75 I are of a suitable length to reach entirely across the chains to the outsides thereof, and the ends of said sticks and the shape of the clips are such as to prevent the sticks from turning in said clips, each clip and each end 80 of each stick being represented as having flat engaging surfaces h i for that purpose. Suitable chain-races g³ g⁴ support the weight of the chains, poles, and skeins above the washing liquid. The back of each stick I extends 85 back of the clip and is longitudinally grooved at i', for a purpose hereinafter explained.

When the machine is in operation, the sticks advance toward the lower squeeze-roll above the washing liquid, said sticks being 90 at all times parallel with each other and with the axis of said feed-roll. The skeins of yarn are hung upon the sticks just as in the operation of skein-washing by hand. The upper squeeze-roll j has a shaft J, turning in journal-boxes j' j², capable of vertical movement in slots c³ in the stands C C', and each journal-box j' j² has a downhanging arm j³, carrying at its lower end an antifriction-roll j⁴,

which rests upon a cam K K', fast on the shaft E, the throw of the cam being such that in every revolution of the lower squeeze-roll e the upper squeeze-roll is raised sufficiently to allow a stick to pass between said rolls, said cams each having a rest or concentric portion k of sufficient angular measurement to hold the squeeze-rolls apart until the stick has passed between said rolls, after which the part k' of the cam allows the upper squeeze-roll to fall upon the skeins trailing from said stick. In this way the skeins are thoroughly squeezed after each immersion.

The upper squeeze-roll falls by its own gravity, which may be assisted by suitable springs (represented in Figs. 1 and 2 as spiral springs $j^5 j^6$) compressed between the sliding journal-boxes $j^1 j^2$ and nuts or tension-blocks $j^7 j^8$, which slide without turning in the slotted stands C C' and are forced down upon said springs by screws $j^9 j^{10}$, which may be turned to adjust the compression of said springs.

Each stick I after passing through the squeeze-rolls is immediately submerged and carried below the surface of the washing liquid to the front end of the tank, trailing the skeins and completely submerging them, the dragging of the skeins through the liquid having the effect to keep the ends of the fibers against the body of the yarn, and thus not only improving the appearance of the yarn and of the cloth woven therefrom, but saving a large amount of the stock or fiber which is wasted in the usual operation of washing skeins by hand, in which it is customary repeatedly to shake the yarns in the washing liquid. The skeins on emerging from the liquid at the front of the tank A are again carried through the squeeze-rolls, and the operation is repeated until the skeins are properly cleaned.

The speed of the squeeze-rolls may be varied by making the intermediate gear f a change-gear—that is, by supporting it upon the movable bracket f' in such a manner that it may readily be changed for another gear of the same pitch, but having a greater or less number of teeth.

In order that the same part of any skein may not always rest upon the stick, and thus escape the action of the squeeze-rolls, the point of support of the skeins upon the stick is changed after every immersion of said skeins by means described below.

A swinging frame, consisting of parallel arms L L', is journaled on bracket-studs l l', secured to opposite sides of the tank A, the upper ends of said arms being rigidly connected by a horizontal bar l'. The frame is swung by a connecting rod or link l', pivoted at one end on the arm L' and at the other end to a wrist-pin l⁴ on the gear f in such a manner that when the frame moves toward the squeeze-rolls the bar l' moves at about the same speed as the chains travel for a distance and then swings in the other direction at the same rate of speed. A supplementary frame,

consisting of a horizontal guide-bar M, a horizontal stud M', and a brace m, connecting said guide-bar and stud, is secured to and moves with the arm L. A horizontal shaft N, journaled in brackets n n', secured on the standard C and tank A, is driven by means of bevel-gears n² e⁴, fast on said side shaft and on the shaft E of the lower squeeze-roll, respectively. The front end of the shaft N carries a cam O, fast thereon, Fig. 6, and having a cam-groove o, which receives a horizontal stud p, which is secured on the upper end of a shifting lever P, pivoted at p' on an arm n³, which projects from the bracket and is arranged below and parallel with the shaft N, said stud p preferably carrying an anti-friction-roll p² within the cam-groove o. The shifting lever P below its pivot p' is connected by a link or connecting-rod p³ to an intermediate lever Q, the latter being pivoted at q on the stud M' below said link p³, the upper end of said lever Q being connected by another link q' to a block or carriage R, which slides on the guide-bar M at right angles to the chains G G' when the cam O is rotated. The carriage R supports a horizontal shifting rod r, which by the movement of said carriage toward the chains G G' is made to reach across both said chains below the top of any stick I, and the swinging of the frame L L', and therefore of the supplementary frame, including said guide-bar M, is so timed with reference to the position of the sticks and the position of the cam O that the inner or free end of the shifting rod I in crossing the nearest chain G enters the groove i' in the back of a stick I between said stick and the skeins supported thereon and continues in said groove until said free end of said rod r projects from the farther end of said groove i', said rod while passing through the skeins also traveling toward the squeeze-rolls at the same speed as said stick. When the shifting rod I has passed entirely through all the skeins on a stick, the motion of said shifting rod toward the rolls is reversed, and said rod and stick separate, causing the upper parts of the skeins on the stick to be drawn away from the squeeze-rolls and bringing other parts of said skeins on said stick, the endwise movement of the shifting rod being suspended while the stud p is in the concentric part o' of the cam-groove o and until the rod and stick have separated sufficiently for the yarn-shifting purpose above described, when said rod is withdrawn from said skeins. The longitudinal movement of the carriage and shifting rod toward the chains is due to the action of the part o² of said cam-groove and the return movement to the part o³ of said cam-groove on the lever P.

The shifting rod r should be very stiff to support the weight of the yarns and is sustained and guided by a bracket l⁵, secured to the back of the arm L through a hole l⁶, in which said rod slides, as shown in Fig. 1. Inasmuch as the lever P has merely a mo-

tion on its stationary fulcrum, while the lever Q swings with the supplementary frame, it is necessary that the opposite ends of the link p^3 should be connected to said levers by some means which will allow each end of said link to have two motions on the corresponding lever. I therefore provide at each end of said link p^3 a ball-and-socket connection p^4 q^2 of said link to the levers P Q.

10 I claim as my invention—

1. In a skein-washing machine, the combination of a suitable tank, squeeze-rolls, two parallel endless chains, running at opposite ends of said rolls, at right angles with the axis of said rolls, skein-supporting sticks, carried by said chains at equal intervals at right angles to said chains, and positive means of varying the distance apart of said rolls at regular intervals of time, to allow said sticks 20 to pass between said rolls.

2. The combination, in a skein-washing machine, of a suitable tank, stands, supported thereon, a lower squeeze-roll, journaled in stationary bearings in said stands, an upper 25 squeeze-roll, parallel with said lower squeeze-roll, journal-boxes, movable toward and from said fixed bearings and supporting said upper squeeze-roll, cams, rotary with said lower squeeze-roll, to move said journal-boxes away 30 from said fixed bearings, two parallel endless chains, running at opposite ends of said rolls at right angles thereto, and skein-supporting sticks, carried by said chains, parallel with said rolls.

35 3. The combination, in a skein-washing machine, of a suitable tank, the squeeze-rolls, two parallel endless chains, running at opposite ends of said squeeze-rolls, a skein-sup-

porting stick, carried by said chains parallel with the axes of said squeeze-rolls, a movable 40 guide, arranged parallel with said stick, means of causing a lateral reciprocating intermittent movement of said guide, equal in speed with the movement of said stick, a carriage, traveling on said guide, a shifting rod, supported by said carriage, means for reciprocating said carriage, to thrust said rod through the skein supported on said stick during the movement of said guide with said stick and means for increasing the interval between 50 said rod and stick.

4. The combination, in a skein-washing machine, of a suitable tank, the squeeze-rolls, two parallel endless chains, running at opposite ends of said squeeze-rolls, a skein-supporting stick, carried by said chains parallel with the axes of said squeeze-rolls, a movable guide, arranged parallel with said stick, means of causing a lateral reciprocating intermittent movement of said guide, equal in speed with 60 the movement of said stick, a carriage, traveling on said guide, a shifting rod supported by said carriage, means for reciprocating said carriage, to thrust said rod through the skeins supported on said stick during the movement 65 of said guide with said stick, means for increasing the interval between said rod and stick, and means of subsequently withdrawing said rod from said skeins.

In witness whereof I have hereunto set my 70 hand in presence of two witnesses who have signed below.

ROBERT E. MURPHY.
